UNITED STATES PATENT OFFICE.

FERDINAND R. HASSELHOFF, OF CINCINNATI, OHIO, AND CHARLES MAYNC,
OF NEW YORK, N. Y.

SHELF FOR STOVES.

SPECIFICATION forming part of Letters Patent No. 237,526, dated February 8, 1881.

Application filed December 9, 1880. (No model.)

To all whom it may concern:

Be it known that we, FERDINAND R. HASSELHOFF, a citizen of the United States, residing at Cincinnati, in the county of Hamilton and State of Ohio, and CHARLES MAYNC, a citizen of the United States, residing at New York, in the county and State of New York, have invented a new and useful Improvement in Shelves for Stoves or Ranges, of which the following is a specification.

This invention relates to that class of stoves or ranges in which a plate is arranged to slide on the floor of the oven, and is provided with a revolving grate connected with the sliding plate by a central pivot-pin.

The object of our invention is to render this class of devices more simple and less expensive than heretofore, to dispense with the central pivot-pin, and to permit the revolving grate to be readily detached from or applied to the sliding plate.

This invention is illustrated in the accompanying drawings, in which Figure 1 represents a horizontal section, showing the sliding plate moved to an outer position in the oven. Fig. 2 is a cross-section of the two plates. Fig. 3 is a front view, with a portion of the brace broken away to expose other parts. Fig. 4 is a longitudinal section on the line *x x*, Fig. 3; and Fig. 5 represents a transverse sectional view of the sliding and revolving plates, showing the same separated from each other.

Similar letters indicate corresponding parts. The letter *A* designates the oven, *B* the sliding plate, and *C* the revolving plate. The oven *A* occupies the usual place in a stove or range, and the sliding plate *B* is fitted into it, while the revolving plate *C* rests on the sliding plate. In this example the sliding plate *B* is placed directly on the bottom of the oven *A*, and it is provided with a lug, 10, which is fitted between guide-rails 11 on such bottom; but, if desired, it may be arranged in an elevated position on suitable cleats. The revolving plate *C* is constructed with a circular flange, 12, (see Fig. 2,) which is sunken into a corresponding hole, 13, in the sliding plate *B*, for the purpose of guiding or keeping the revolving plate in its position, and this plate is also preferably constructed with bifurcated arms 14, to receive a key or wrench for turning the same.

It will be readily perceived that if the utensil—as a pan—containing the article to be baked is placed on the revolving plate *C*, and the sliding plate *B* is pulled out of the oven—as 55 to the position shown in Figs. 1 and 4—one is enabled to inspect the article, and, if found expedient, to alter its position without touching the pan, and hence the burning of one's fingers is avoided. 60

To the lower and central part of the sliding plate *B* is pivoted a brace, *D*, which serves to sustain the same in the position shown in Figs. 1 and 4. In this example the stove is provided with a step, 15, to receive the free end of the 65 brace *D* when it is applied to use; but, if desired, such end of the brace may be allowed to rest directly on the floor.

When the brace *D* is not in use it is swung up beneath the sliding plate *B*, and in that 70 position is shoved into the oven, namely, between the guide-rails 11, together with the sliding plate; and, in order to leave a space beneath the sliding plate for the reception of the brace, it is provided with rails or runners 16. 75

The motion of the sliding plate *B* is limited by means of stops 17 co-operating with counter stops 18; but these stops are so constructed as to allow the removal of the plate from the 80 oven. At or near one of its edges the sliding plate *B* is provided with lugs or ears 19, while in the top *A'* of the stove are formed sockets 20, adapted to receive the lugs or ears, so that, if desirable, the sliding plate can be taken out 85 of the oven and attached to the top of the stove, as indicated in dotted outline in Fig. 3. When the sliding plate *B* is brought to the place last named the brace *D* is used to assist in its support, the free end of the brace being 90 placed on a step, 21, Fig. 3, applied to a suitable part of the stove or being placed on the floor. It may be remarked that the lugs 19 and sockets 20 can be transposed.

The stops 17 18, moreover, can be applied to 95 the rails 11 without departure from our invention.

What we claim as new, and desire to secure by Letters Patent, is—

1. The combination, with the oven of a stove 100 or range, of the sliding plate *B*, constructed with a circular opening, 13, and the revolving

plate C, constructed with a depending flange, 12, detachably arranged within the circular opening of the sliding plate, and guided by the edges of the same in its rotary movements, substantially as shown and described.

5 2. The combination, with the oven of a stove or range provided on its bottom with the guide-rails 11 and side stops, 17, of the sliding plate B, provided with the depending lug 10, fitting between the guide-rails, the rails or runners 16, and the corner-stops 18, co-operating with the stops 17, and the detachable plate C, adapted to rotate in a seat in the sliding plate, all substantially as described.

15 3. The combination, with the oven of a stove or range and an exterior step, 15, on the exterior of the same, of the sliding plate B, arranged on the bottom of the oven, and provided with a rotating plate, C, and a brace-bar, D, pivoted to the under side of the sliding plate, and adapted to drop by gravity and

rest upon the step 15 when the said plate is extended, substantially as shown and described.

4. In a stove or range, provided with an oven, and with the side step, 21, and sockets 20 25 in its top flange, the plate B, having lugs or ears 19, and pivoted brace D, adapted to be attached to and detached from the sockets 20 and the step 21, respectively, substantially as described.

30 In testimony whereof we have hereunto set our hands in the presence of two subscribing witnesses.
